Richard B. Daven.
ATTORNEY.

UNITED STATES PATENT OFFICE.

HOWARD LOCKHART, OF FALLS CITY, NEBRASKA, ASSIGNOR TO EMMA L. VERNON, OF AKRON, COLORADO.

TANK HEATER.

Application filed March 3, 1921. Serial No. 449,447.

To all whom it may concern:

Be it known that I, HOWARD LOCKHART, citizen of the United States, residing at Falls City, in the county of Richardson and 5 State of Nebraska, have invented certain new and useful Improvements in Tank Heaters, of which the following is a specification.

This invention relates to new and useful 10 improvements in tank heaters and more particularly to the type designed to be submerged in a body of liquid for heating the same.

An important object of the invention is 15 to provide a heater of the above type embodying a construction and arrangement rendering it comparatively simple to feed fuel to the device and remove ashes and other accumulations therefrom. 20 Another important object of the invention is to provide a device wherein water backs are disposed in the path of heat ensuing from the fire within the device.

Other objections and advantages of the 25 invention will become apparent in the course of the following description.

In the accompanying drawings forming a part of this application and wherein like numerals are employed to designate like 30 parts throughout the several views,

Figure 1 is a vertical section through the device showing the same submerged.

Figure 2 is a fragmentary horizontal section taken on the line 2—2 of Figure 1.

Figure 3 is a similar view taken on the line 3—3 of Figure 1 and

Figure 4 is a perspective view of one of the water backs employed in the device.

Figure 5 is a detail view illustrating a 40 modified connection of the chimney.

Referring now to the drawings wherein for the purpose of illustration is shown the preferred embodiment of my invention, the numeral 5 indicates the tank heater 45 in its entirety and which consists of a body portion 6 which is here shown as being substantially rectangular in configuration, but it is of course to be understood that any other shape may be employed. This body portion consists of top 7, ends 8, sides 9 and a bottom 10 which is adapted to rest upon the bottom of a tank 11 or other receptacle containing a liquid.

One end 8 of the body portion is open and provided with an upwardly inclined 55 chute 11 which extends a substantial distance above the top of the body portion to be disposed above the level of the water placed in the receptacle or tank to be heated. The top of this chute is equipped with a 60 hinged cover 12 which is provided with an air intake opening 13 controlled by a damper or hinged lid 14 pivoted to the cover 12. It will of course be understood that both the cover 12 and the damper 14 65 may be opened or closed at will. It is also to be noted that the bottom of the chute 11 adjacent the body portion of the heater is arcuated as at 15 to provide a slide for a purpose which will be hereinafter explained. 70

A horizontal grate 16 is positioned within the body portion of the device and is arranged a substantial distance from the bottom thereof to divide the body portion into a combustion chamber 17 thereof and an ash pit or chamber 18 below the grate. 75

A door 19 which when closed is arranged vertically is pivotally connected at its lower end as at 20 to the end of the grate adjacent the chute 11. The upper end of this door is adapted to slightly engage the top of the body portion 7 at its juncture with the top or relative upper portion of the chute when the door is arranged in a closed 80 position. 85

In order that the door may be easily controlled from the upper end of the chute, the rod 21 has one end pivotally connected to the relative upper end of the door, while the opposite end of the rod extends to a point adjacent the cover of the chute and is adapted to rest upon the inclined bottom of the chute as is clearly shown in Figure 1. 90 To retain the door 19 in a closed position and to prevent the same from accidentally swinging open, means in the form of an upstanding lug 22 is formed upon the inclined bottom of the chute adjacent the upper end thereof whereby the free end of the rod 21 may abut the same. When it is desired to feed fresh fuel to the grate or fire, the cover 12 of the chute is raised to permit access to be had to the rod 21. The free end of this rod is moved to disengage the 95 same from the lug 22 and is pulled out 100 105

wardly of the open end of the chute thereby causing the door 19 to swing outwardly of the body portion into the chute until the upper end of the door rests upon the inclined bottom of the chute. When the door is in this open position, as clearly seen in Figure 1, it will incline downwardly toward the grate 16. Consequently any coal or fuel dropping from the shovel conveying the same into the body portion will fall upon the bottom of the chute or the door and will therefore be caused to be conveyed onto the grate upon closing of the door.

A substantially U-shaped water back 23 is disposed horizontally within the body portion above the grate, and is secured to the walls of the body portion in any suitable manner. The bridging portion of the U-shaped water back is provided with an inlet nozzle or pipe 25 and a similar outlet 26 which projects through openings in the end 8 of the body portion to admit into and discharge from the water back.

A horizontal partition 27 extends entirely across the body portion and from end to end thereof, the end of the partition 27 adjacent the chute being angularly disposed vertically to provide an abutment 28 for the door 19 when the same is arranged in a closed position. This partition is provided with an opening adjacent the end 8 of the body portion so that heated air may be directed into the body portion above the partition to be discharged through a chimney 29 communicating with the top of the body portion adjacent the chute. However, I do not desire to limit myself to the location of the chimney with respect to the body portion as it may be efficiently positioned as shown in Figure 5 to communicate with the combustion chamber through the end 8 of the body portion. In either event, the chimney is equipped with a spark arrester 30 and extends well above the level of the water being heated.

A hinged lid or damper 31 is pivotally connected to the partition adjacent the opening therein so as to control the flow therethrough. A rod 32 is pivotally connected to this damper and extends through the combustion chamber, and an opening in the door 19 and into the chute 11 whereby it may be conveniently reached for operating the damper. This damper it will be noted, is of such dimension as to cause the same to be inclined when in a closed position due to its abutment with the end wall 8. Consequently, when the chimney 29 is associated with this end wall, the damper 31 will act to efficiently control the passage of heated air thereto.

A second water back 33 is arranged above the partition 27 and is supported in a horizontal plane thereon. This water back is 65 also U-shaped and the free ends of the arms

thereof are equipped with nozzles 34 adapted to extend through the end 8 of the body portion whereby water may pass into the water back and exit therefrom after becoming properly heated.

A relatively small ash pan 35 is adapted to rest upon the bottom of the body portion beneath the grate to receive ashes and cinders discharged therefrom. This ash pan assumes the form of a scoop having its forward end removed and provided with an upturned portion 36 forming a hook with which a suitable implement may be engaged for withdrawing the pan from the ash chamber and through the chute. The arcuated portion of the chute will serve to assist in the removal of the ash pan.

The foregoing description and accompanying drawings have reference to what might be considered to be the approved or preferred form of my invention. I desire it to be understood that I may make changes in the construction, combination and arrangement of parts, materials, dimensions, etc., as may prove expedient and fall within the scope of the appended claims.

Having thus described my invention what I claim as new and desire to secure by Letters Patent is:

1. In a tank heater comprising a body portion having a chute communicating therewith, a grate in said body portion, a horizontal partition above the grate, a water back arranged directly above the grate, and a second water back supported upon the partition.

2. A tank heater comprising a body portion having a chute communicating therewith, a grate in said body portion, a horizontal partition above the grate, a damper hinged to said partition, and an operating rod connected to the damper and extending into said chute.

3. A tank heater comprising a body portion having a fire box, a horizontal partition arranged above the grate therein to provide the body portion with an upper heat chamber above the partition, said heat chamber and fire box having communication, and damper means for regulating communication between said fire box and heat chamber.

4. A tank heater comprising a fire box, a partition therein dividing the fire box into upper and lower chambers, said chambers being in communication adjacent one end of the fire box, and a chimney rising from the fire box at the other end thereof.

5. In a tank heater comprising a body portion, a grate in said body portion, a water coil arranged directly above the grate and a second water coil supported above the first mentioned coil.

6. A tank heater comprising a body portion, a grate in said body portion, a hori-

zontal partition above the grate, and a water coil arranged directly above the partition.

7. A tank heater comprising a body portion, a chute extending therefrom, a grate in the body portion spaced from the bottom thereof, a door hinged adjacent the grate and adapted to be arranged in a vertical position when in a closed position, a rod connected to the door and extending up

into the chute, and means in the chute adapted for engagement with the rod to retain the same in a position to maintain the door in a closed position.

In testimony whereof I affix my signature in presence of two witnesses.

HOWARD LOCKHART.
